Primary Examiner—Cathron Brooks

(74) Attorney, Agent, or Firm—Mark B. Garred; Stetina
Brunda Garred & Brucker(57) **CLAIM**The ornamental design for a container carrying device, as
shown and described.**DESCRIPTION**FIG. 1 is a front right side perspective view of the container
carrying device of the present invention showing my new
design, the broken line depictions of the container, belt, and
support panel being for illustrative purposes only and forming
no part of my new design;FIG. 2 is a top plan view of the container carrying device,
shown in an unfolded position, the broken line depiction of
the support panel being for illustrative purposes only and
forming no part of my new design;FIG. 3 is a right side elevational view of FIG. 2, the left side
elevational view being a mirror image of the right side
elevational view;

FIG. 4 is a bottom plan view of FIG. 2;

FIG. 5 is a front elevational view of FIG. 2; and,
FIG. 6 is a rear elevational view of FIG. 2.**1 Claim, 2 Drawing Sheets***Fig. 1**Fig. 5**Fig. 2**Fig. 3**Fig. 4**Fig. 6*
